(57) **CLAIM**

The ornamental design for "USB charger for electronic cigarette device," as shown and described.

DESCRIPTION

FIG. 1 is a front, bottom and left side perspective view of the first embodiment for USB charger for electronic cigarette device showing my new design;

FIG. 2 is a front, bottom and left side perspective view of FIG. 1 with an electronic cigarette device inserted therein;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1; and,

FIG. 8 is a bottom plan view of FIG. 1.

The broken lines are for illustrative purposes only and form no part of the claimed design.
